UNITED STATES PATENT OFFICE

RAYMOND E. BOHRER, OF ROCHESTER, NEW YORK, ASSIGNOR TO THE TODD COMPANY, INC., OF ROCHESTER, NEW YORK, A CORPORATION OF NEW YORK

LOOSE-LEAF BINDER

Application filed June 10, 1926. Serial No. 115,041.

This invention relates to loose-leaf binders and more particularly to the flat opening variety adapted, for example, for check books, ledgers and folios where it is desirable 5 to have the pages open in a flat condition to afford an even surface for writing, one object of the invention being to provide an improved binder of this character having a simple and efficient form of construction adapted 10 to be quickly and conveniently operated and to hold the paper leaves securely and also so that they may be readily removed or replaced. Another object is the provision of such a 15 binder having simple, practical and inexpensive leaf-retaining means normally securely locked but capable of being quickly adjusted to release the leaves with a minimum of time and effort. A further object is the provision of a binder having leaf-retaining 20 means of the above character detachably associated with a cover portion in a simple, convenient and inexpensive form of construction.

To these and other ends the invention resides in certain improvements and combinations of parts, all as will be hereinafter more fully described, the novel features being pointed out in the claim at the end of the specification.

30 In the drawings:

Figure 1 is a top plan view of a loose-leaf binder embodying the present invention, showing the front cover portion swung open;

Figure 2 is a side elevation of the same 35 showing the front cover portion in closed position;

Figure 3 is an enlarged front elevation of the sheet-retaining means detached;

Figure 4 is a side elevation of the binder 40 showing the parts in position for inserting or removing the leaves;

Figure 5 is an enlarged perspective view of the leaf retaining arch member detached;

Figure 6 is a similar view of plate means 45 for holding the leaf retaining arms, showing the parts thereof partially formed; and

Figure 7 is a perspective view showing the leaf retaining arm means and hinged plate therefor fixed to a backing member detached from the cover.

Similar reference numerals throughout the several views indicate the same parts.

The invention is disclosed herein, by way of illustration, in an embodiment comprising 55 cover means having a back portion 10 and a front portion 11 hinged thereto, as by means of a flexible hinge strip 12, and the cover may include also a binding section 14 secured to hinge strip 12 and to the front portion proper as by means of a second flexible strip 15, as 60 well understood in the art. The cover back is preferably formed with a pocket as by means of a lining 16 secured thereto along the top, bottom and right hand end of the back, leaving the left-hand edge free to form 65 the pocket opening.

The sheet or leaf retaining means proper is detachably inserted in the cover pocket so that it is removable with the leaves as a unit, as may be desirable, for example, after 70 the leaf-retaining means has been filled and it is desired to separate the cover for use with a new retaining means. To this end the retaining means preferably comprises a backing member 17 in the form of a sheet of relatively stiff cardboard, for example, to which the devices proper for detachably engaging 75 the leaves are secured.

The leaf-engaging means proper comprises, preferably, one or more sheet metal 80 parts or plates 18, as best shown in Figures 6 and 7. These plates have pointer lugs 19 struck therefrom and adapted to be forced through the backing member 17 and clinched on the underside of the latter to securely fix 85 the plate thereto, although, of course, the plates may be secured to the backing member in other ways. Plate 18 is formed along its rear edge with a hinge loop 20 rolled inwardly from the margin as shown. The opposite margin of the plate is raised or offset 90 upwardly as at 21 and the opposite edges 22 of the plate portion 21 afford locking edges for the leaf-retaining arms as hereinafter described. Figure 6 shows the plate 18 with 95 the hinge means or loop 20 partially formed and with the securing lugs 19 bent at right-angles to the plate ready for insertion through the backing member 17.

The leaf-retaining means or posts for each 100

plate are preferably formed of a single length of wire of suitable gauge and material to afford a relatively stiff but resilient member which is shaped and formed as best shown in Figure 5. Thus, the wire has a straight central hinge portion 23 adapted to be engaged under the plate hinge loop 20 when the latter is bent down into final position. At the ends of the pintle portion 23 the wire is bent upwardly at right-angles as at 24, thence forwardly in an arc as at 25 and thence downwardly as at 26 parallel with the portions 24, to afford arms or arches of substantial radius for retaining the desired quantity of leaves. The arch portions 26 have their extreme ends beveled as at 27 and are formed adjacent thereto with shoulders or notches 28 to adapt these portions to spring over the edges 22 of plate 18 as the arch is closed with the notches 28 securely locked with the edges 22 as shown in Figure 7.

It is apparent from the above construction that the backing member 17 may be quickly associated with a cover by inserting it in the cover pocket, as shown in Figure 1, for which purpose the edges of the backing member may be beveled as at 29. With the parts so arranged, the cooperating pair of arches 26 of each leaf-retaining device may be quickly and conveniently spread or sprung apart by engaging the hand with one arch as a rest or fulcrum and pressing the finger against the other arch to release the arches from the hinged plate 18. The arch portions may then be pivotally swung back to the position shown in Figure 4 and one or more leaves placed thereon and inserted in position in the cover, after which the arches are swung pivotally forward and downward. In the latter position a slight downward pressure on the arches, by reason of their beveled ends, causes them to spring over the edges 22 of the locking plate portion 21, in which position the arches are securely held with the leaves bound in the cover. It has been found that the construction described for the leaf-retaining arches is particularly advantageous in that the relatively stiff wire required may be readily sprung and released in the manner described with but a slight pressure applied by one hand between the pair of arches which, however, are normally securely held in locked position by the engagement of their notched portions with the edges of the plate 18 from which no inadvertent force on the leaves or binder can release them.

Any desired number of leaf arches or posts may be employed, two being shown in the present instance. The arch portions themselves, as well as the hinge and locking plates 18 are simple, effective and inexpensive in construction and readily assembled with each other and with the backing member 17 and the detachable association of the latter with the cover adds to the convenience and utility of

the binder in that when the latter has been filled, the file of leaves may be removed as a unit with their retaining means, for filing or other purposes, and a new retaining means provided for the cover.

70

I claim as my invention:

A retaining element for holding loose leaf sheets in a binder comprising a plate adapted to have one side thereof secured to a backing member, one edge of said plate being bent to form a tubular bearing portion substantially tangent to said plate on the side opposite to that to which the backing member is applied, the opposite edge of said plate being bent to form a portion extending in the same direction as the body of said plate and offset from the plane of said body on the same side thereof as said tubular portion, and a wire having an intermediate portion journaled in the tubular portion of said plate and a loop formed at each end of said intermediate portion, each loop lying in a plane perpendicular to the plane of said plate and on the same side of said plate as said tubular portion and offset portion, the end of each loop having a notch for engagement with an edge of the offset portion of said plate.
